UNITED STATES PATENT OFFICE.

ISAAC O. RUSSELL, OF INDIANAPOLIS, INDIANA, ASSIGNOR TO JAMES T. HORN, OF INDIANAPOLIS, INDIANA.

PHYSICAL EXERCISING DEVICE.

No. 820,017.

Specification of Letters Patent.

Patented May 8, 1906.

Application filed January 12, 1906. Serial No. 295,826.

To all whom it may concern:

Be it known that I, ISAAC O. RUSSELL, a citizen of the United States, residing at Indianapolis, in the county of Marion and State 5 of Indiana, have invented certain new and useful Improvements in Physical Exercising Devices, of which the following is a specification.

This invention relates to improvements in 10 physical exercising devices to be used for building up and strengthening the muscles and which may also be used as a toy.

The invention consists of a circular plate 15 of wood having a handle extension, together forming a paddle. A ball, preferably a hollow rubber one, is connected by a rubber string with the outer end of the paddle. The plate at this outer end is provided with a central opening circular in shape and slightly 20 smaller in diameter than the diameter of the ball.

The object of the invention is to provide a 25 device for catching and holding the ball by drawing the latter partially through the hole, when the return of the ball by the action of 30 the rubber is accurate enough to deliver it properly to the hole. In devices of this character as heretofore made the hole has been large enough to allow the ball to pass freely 35 through, and it has been caught in a pocket at the back of the paddle; but owing to the force with which the ball enters the pocket the latter soon becomes torn and destroyed.

I have found that by making the hole approximately 40 one-sixteenth of an inch less in diameter than the ball that the ball by skilful driving can be passed sufficiently through the hole to be caught and retained in the paddle until expelled by a counter-pressure; and a further object of the invention, therefore, is 45 to cheapen the cost of manufacture of a physical exercising device and render the same more durable.

I accomplish the objects of the invention 50 by the mechanism illustrated in the accompanying drawings, in which—

Figure 1 is an edge view of the paddle with a ball caught in the opening through the paddle. Fig. 2 is a longitudinal section on the 55 line 2 2 of Fig. 3, and Fig. 3 is a front view of the paddle with the ball removed from its opening.

Like characters of reference indicate like parts throughout the several views of the drawings.

4 is the circular plate at the end of the paddle, and 5 is the handle, which will preferably be made wide enough to receive inscriptions or printed matter in the way of directions or advertisements should the article be used as 60 an advertising medium.

6 is an elastic ball, preferably a hollow rubber ball, and it is connected with the end 4 of the paddle by means of the rubber string

7. The circular plate 4 of the paddle has a 65 central hole 8, slightly smaller in diameter than the diameter of the ball, the dotted lines circling around the hole 8 indicating the size of the ball.

In using this device the operator grasps the 70 handle 5 with one hand, strikes the ball a blow with the plate 4, driving it away from him in any desired direction, thereby bringing into play the different muscles of the body in bending to keep in the direction of 75 the ball. The ball will be drawn back by the elasticity of the rubber string, and if it strikes the hole 8 squarely from in front of the paddle it will enter the hole and its walls will be compressed in the manner shown in Fig. 2, so 80 as to require positive dislodgement by a pressure upon the ball from the rear of the paddle.

Having thus fully described my invention, what I claim as new, and wish to secure by Letters Patent, is—

1. In a physical exercising device, a paddle, an elastic ball, an elastic string connecting the ball with the paddle, said paddle having a perforation slightly less in diameter than the diameter of the ball adapted to 90 catch and hold the ball.

2. In a physical exercising device, a paddle, a hollow rubber ball, a rubber string connecting the ball with the end of the paddle, said paddle having a hole slightly less in diameter than the ball to catch and hold the ball.

In witness whereof I have hereunto set my hand and seal, at Indianapolis, Indiana, this 23d day of September, A. D. 1905.

ISAAC O. RUSSELL. [L. S.]
